UNITED STATES PATENT OFFICE.

MARK L. BRILLIANT, OF SAN FRANCISCO, CALIFORNIA.

DAVENPORT BED.

1,404,508.

Specification of Letters Patent.

Patented Jan. 24, 1922.

Application filed October 16, 1919. Serial No. 331,111.

To all whom it may concern:

Be it known that I, MARK L. BRILLIANT, a citizen of the United States, residing at the city and county of San Francisco and State of California, have invented new and useful Improvements in Davenport Beds, of which the following is a specification.

This invention relates to a davenport, and especially to a davenport which may be unfolded to form a bed.

One of the objects of the present invention is to provide a davenport bed of simple and compact construction, which, when folded, shows no indication that it may be employed as a bed and, when unfolded, presents a wide mattress resiliently supported for use without employing any of the upholstered sections, such as the seat or the back-rest. Another object of the invention is to provide a sectional, foldable mattress frame which is adapted to carry a mattress support constructed of coil springs, said sectional frame, when folded, being so arranged within the main frame of the davenport that ample space is provided for the springs, the mattress and the bedding. Another object of the invention is to provide a bed, the foldable sections of which will counterbalance each other during the extending or folding of the bed, thus rendering it comparatively easy for anyone to manipulate the same. Another object of the invention is to provide a main frame which is sectional in construction and provided with a novel mounting for the sectional bed frame which permits it to be readily removed, with relation to the main frame, for instance during transportation or storage. Another object of the invention is to provide a link and lever between the sectional mattress frame sections which permit movement of one section to be transmitted to extend and elevate the other section with relation to the main frame when the bed is extended and reverse movement when the bed is folded; in this manner providing ample space for the bedding contained between the foldable mattress supporting frame sections. Further objects will hereinafter appear.

Referring to the accompanying drawings:

Fig. 1 is a perspective view of the davenport bed showing the same extended.

Fig. 2 is a sectional, end view of the davy-

port showing the mattress frame sections in folded position.

Fig. 3 is a detail, plan, sectional view of one end of the bed, showing the manner of supporting the lower mattress frame sec- 60

Fig. 4 is a detail end view of the hinged connection formed between the main frame and the back-rest.

Fig. 5 is a diagrammatic view, showing 65 the mattress frame sections partly unfolded.

Fig. 6 is a similar view, showing the mat- tress frame sections completely unfolded.

Referring to the drawings in detail, A indicates, in general, the main frame of a 70 davenport, 2 the end sections and 3 the rear side of the davenport. Mounted within the main frame section, between the end sec- 75 tions 2, is a lower mattress frame 4 and an upper mattress frame 5. These sections are hingedly connected by means of a pair of links 6, one disposed at each end of the frames. The lower frame 4 is supported by means of a pair of links 7. These links are attached at one end to a bar 8 which is se- 80 cured to the lower frame 4, while the oppo- site ends are pivotally secured in a bar 9. The bar 9 is supported at one end, as at 10, in an angle iron bracket 11 secured to the forward post 12 of the end sections 2; the 85 opposite end of the bar 9 being supported by a pin 14 which is secured by an inter- mediate post 15 forming part of the end frame 2.

There are two bars 8, one at each end of 90 the lower frame 4, two bars 9, two pairs of links 7 and also two angle plates 11 and pins 14; that is, the parts are arranged in duplicate at each end of the lower frame. The lower frame, hinged or supported by 95 the links 7, is box-like in construction and forms a support for a series of cross slats 17, upon which are mounted coil springs and a mattress 19. The lower frame also serves as a support for the upper frame 5 100 when this assumes its folded position, as shown in Fig. 2. The upper section 5 merely serves as a support for the mattress when the frame sections are extended and it nor- mally serves the function of a seat for the 105 davenport which is upholstered, as shown at 20. The frame 5, when extended, other- wise supports the mattress 19, and as cross slats and springs 21 are secured within the upper frame section 5, it can be seen that a 110

continuous resilient support is provided for the mattress 19 when the frame sections are extended.

For the purpose of providing as much space as possible between the frame sections when folded for the reception of a mattress, bedding, etc., I have provided means for raising and lowering the lower frame 4. This is accomplished in the following manner: Pivots attached to the forward end 10 of the upper frame 5 is a pair of links or motion bars 22. These links or motion bars are disposed one at each end of the upper frame; the upper ends thereof being pivotally attached to the frame 5, as shown at 23, and the lower ends to the pins 10 secured in the angle brackets 11. This connection between the angle brackets 11 and the upper frame permits swinging movement of the upper frame when this is extended and it simultaneously imparts movement to the lower frame 5 through the link connection 6, as will be described.

When extending the bed, it is necessary 25 to lift the upper frame in the direction of arrow *a* (see Fig. 2). This will cause the frame 5 first to assume the position shown at 5^a (Fig. 5) and finally the position shown at 5^b (Fig. 6), when the frame 5 has been 30 completely extended. The radius about which the upper frame 5 swings is determined by the length of the links or motion bars 22; and as the upper frame is connected with the lower frame by means of the links 35 6, it can readily be seen that the lower frame will be pulled forward a predetermined distance when the upper frame is completely extended; the forward pull exerted being transmitted through the links 6. Forward 40 movement of the lower frame, caused by the pull on the links or motion bars, will impart swinging movement to the links 7. These will, therefore, move from the position shown in Fig. 2 to the position shown in 45 Fig. 5 and finally to the vertical position shown in Fig. 6, thereby moving the frame a predetermined distance forward and simultaneously elevating the same with relation to the main frame.

50 The lower frame is in this manner rigidly supported, when elevated and extended, as the links 7 assume a vertical position and the upper frame 5 is simultaneously rigidly supported as permanent legs 24 are secured 55 to said frame at the forward end and the links 22 to the rear end, said links forming a support for the rear end of the upper frame, when extended, as the inner ends of the links will engage the tops of the angle brackets 11 (see Fig. 6), thereby forming a 60 stop which limits the swinging movement of the links 22 and also permits the links to form a support for the inner end of the upper frame.

65 When the bed is folded, reverse movement

takes place; that is, the links 7 will gradually swing backward until the position is assumed, as shown in Fig. 2. This pulls the lower mattress frame back into the main frame and at the same time lowers the same 70 to the position shown. This is of great importance as it permits a greater spacing between the upper and lower frames and also reduces the height of the upholstered seat section 20.

75 The main frame is in this instance provided with a detachable upper section, generally indicated at B, said upper section consisting of a rear frame 30 and a pair of end sections 31; the rear frame 30 and the end 80 sections 31 being secured to the arms or end sections 2 of the main frame by dowel pins, as indicated at 32 in Fig. 2. This upper section is removable to permit the bed to be easily handled, for instance, when moving from place to place and when it is desired to pass the davenport through doors which in some instances may be comparatively small and narrow. The upper frame section is also provided as a support for the 90 back-rest indicated at 34. This back-rest is upholstered or otherwise finished, as indicated at 35, and is attached to the upper frame B by means of a pair of links 36 and intermeshing segmental gear sections 37. 95

100 The mounting of the back-rest as shown is important as it permits this to be removed in unison with the upper frame when it is desired to detach the same, and it also permits the back-rest to be raised, as shown at 34^a in Fig. 1, when the mattress frame sections are extended. The back-rest 34 furthermore serves the function of hiding the front end of the upper frame 5 and the permanent legs 24 secured thereto.

105 For the purpose of forming a convenient head-rest when the bed is extended, I provide a frame, such as indicated at 40. This frame is hingedly secured, as at 41, to the inner end of the lower frame 4 and is raised 110 and lowered in unison with the same. The head frame 40 assumes an angular position, as shown in Figs. 1, 5 and 6, when the bed is extended, due to the forward movement of the lower frame and a vertical position when 115 the bed is folded, as shown in Fig. 2; a pair of cam-like projections being formed on the rear side 3 of the main frame, as indicated at 45, which are provided as guides upon which the head-rest slides during the folding or unfolding movement of the bed frame sections. The frame sections 4 and 5 are otherwise provided with step-like projections 50 and 51 to maintain the frames properly spaced when folded, said section 50 also 120 serving as a foot rail for the bed when the frames are extended, as shown in Figs. 1, 5 and 6.

125 By referring to Figs. 1, 2 and 3 of the drawings, it can be seen that the whole bed 130

may be easily taken apart for shipment or storage or to permit easy handling of the bed when moving; that is, the upper frame B, together with the back-rest, may be removed if desired or the mattress frame sections 4 and 5 may be removed by merely releasing the angle brackets 11 and the front board placed in front thereof.

The removal of the front board and releasing of the brackets 11 permit the frames 4 and 5 to be lifted or pulled forwardly out of the main frame as the inner ends of the supporting bars 9 are slotted, as at 14^a, to permit the same to become quickly and easily released with relation to the pins 14 supporting the same. The bed can, therefore, practically speaking, be taken entirely apart with comparatively little effort and may be assembled just as readily. Only few connections are required and no adjustment is necessary as all parts assume fixed positions when assembled.

Having thus described my invention, what I claim and desire to secure by Letters Patent:

1. A davenport comprising a main frame, a pair of end frames secured thereto, a foot board also connecting the end frames, a pair of links pivotally secured at their lower ends to the end frame, a lower mattress frame section supported thereby, a pair of links pivotally attached to the front end of the mattress frame, an upper mattress frame section pivotally attached to the opposite ends of the links, said links connecting the two mattress frame sections and forming spacers therebetween, a pair of motion bars pivotally attached at their lower ends in the main frame, a pivotal connection between the inner end of the upper mattress frame and the upper ends of the motion bars, and stop members carried by the foot board and

the end frames, with which the motion bars are engageable when the mattress frame sections are unfolded and extended.

45

2. In a structure of the character described the combination with the upper folding frame and the links whereby it is connected with the lower frame, of a pair of motion bars disposed one at each side thereof, a pivotal support for one end of each motion bar, a fixed pivotal connection between the swinging end of each motion bar and the inner side of the upper folding frame, and a stop member for each motion bar with which they are engageable to permit the motion bars to support the inner end of the upper frame when extended and to limit the outward movement of the upper frame and the lower frame when in horizontal position.

50

3. In a structure of the character described a main frame, a pair of stop members secured one at each side thereof, a lower bed frame, links supporting said frame in the main frame, an upper bed frame, links pivotally connecting said upper frame with the lower frame, a pair of motion bars pivotally mounted in the stop members, said motion bars having a fixed pivotal connection at their outer free ends to the inner side of the upper frame, and said motion bars being bent to form substantial angle-shaped links which are adapted to engage the upper ends of the stop members to limit the movement of the upper and lower frames and to support one end of the upper frame.

55

In testimony whereof I have hereunto set my hand in the presence of two subscribing witnesses.

MARK L. BRILLIANT.
